UNITED STATES PATENT OFFICE.

OSCAR KOHORN, OF CHEMNITZ, GERMANY.

MANUFACTURE OF FIGURED PILE FABRICS.

1,156,485.

Specification of Letters Patent.

Patented Oct. 12, 1915.

Application filed April 17, 1914. Serial No. 832,643.

To all whom it may concern:

Be it known that I, OSCAR KOHORN, a subject of the King of Saxony, and resident of Chemnitz, Germany, have invented 5 certain new and useful Improvements in the Manufacture of Figured Pile Fabrics, of which the following is a specification.

This invention relates to the production of figured pile fabrics in which the pile 10 loops are formed over wires and in which the pile-threads of the warp are fastened in by a semi-rotatory binding. The pile-loops are thereby so strongly bound in the web that they cannot be pulled out. At the same 15 time, the appearance of the goods is that of a hand-woven Smyrna carpet, because the design is distinctly visible on the wrong side of the goods. The pile-threads of the warp when they do not form pile are stretched in 20 the goods as filling-threads.

In the accompanying drawing, Figures 1, 2 and 3 illustrate diagrammatically the arrangement of the pile-threads of the warp in different positions; Fig. 4 indicates the 25 draft, thread by thread, of the whole binding; Fig. 5 is a small design; and Fig. 6 indicates a section through the goods in the direction of the weft.

The mode of manufacture and binding are 30 as follows:—There exist three heald shafts or leaves 1, 2, 3. Leaf 2 is intended for the backing warps. This leaf receives no rise. Leaf 3 raises and lowers the binding-thread. A series of pile threads of the warp are first 35 of all drawn through a heald, provided with a large eye or several eyes, of leaf 1. In the drawing, Figs. 1 to 3, five pile threads of the warp are united in one run; it is, therefore, intended to produce goods having 40 five colors. The pile threads of the warp are for a second time individually drawn through doup healds which consist of a whole heald and half a heald (Fig. 3)

as is best seen from Figs. 1 to 3. The doup healds are, in conformity with the design lifted by the Jacquard machine. Every time two wefts for the ground have been woven in, one wire is put in. Previous to the first weft, leaf 3 lifts the binding-thread *a*. Previous to the second weft, all the pile 45 threads of the warp are lifted by leaf 1 and all the doup-healds on the right of the binding-thread *a* are lifted from the backing thread. The wire is inserted after the 50 Jacquard machine, in conformity with the pattern shown in Fig. 5, has lifted those 55 pile-threads of the warp to the left, which are to lie over the wire and thus to form the pile. The pattern is formed as shown by Fig. 6 which is a section in the direction 60 of the weft. By drawing the pile thread of the warp around the backing thread *b*, the former receive so firm a position in the web that it is impossible to draw out the 65 pile loops. By these means, the best substitute is provided for a hand-woven Smyrna carpet.

What I claim, is:—

The method of weaving pile fabric having a binding warp, a backing warp, and a pile 70 warp composed of a plurality of pile warps of different colors, which consists in lifting the binder warps to form a shed with the pile warps, passing a weft through said shed, raising the pile threads to form a shed 75 with the binder warps, passing a weft through said shed and doup loops of selected threads of the pile warp under and around the corresponding binding and backing warp threads to form pile loops, sub- 80 substantially as and for the purpose set forth.

OSCAR KOHORN.
